Patented May 31, 1921.

Inventor:
Cecil L. Hollingsworth
By S. G. Fletcher, Atty

UNITED STATES PATENT OFFICE.

CECIL L. HOLLINGSWORTH, OF ST. LOUIS, MISSOURI.

ADJUSTABLE OFFSET TOOL-HOLDER.

1,379,866.

Specification of Letters Patent.

Patented May 31, 1921.

Application filed April 5, 1919. Serial No. 287,825.

To all whom it may concern:

Be it known that I, CECIL L. HOLLINGSWORTH, a citizen of the United States of America, and a resident of the city of St. Louis and State of Missouri, have invented 5 certain new and useful Improvements in Adjustable Offset Tool-Holders, of which the following is a specification.

One of the objects of this invention is to 10 provide an improved adjustable tool holder that can be stationarily held or allowed to revolve relative to the type of machine with which this improved holder is adapted to coöperate.

15 Another object is to provide an offset tool holder with an improved adjustable arrangement relative to adjusting the tool to and from center.

A further object is in providing a tool 20 holder with an improved tool clamping jaw.

Other and further objects will appear in the specification and be specifically pointed out in the appended claims, reference being had to the accompanying drawings exemplifying the invention, and in which,

Figure 1 is a vertical section taken through this improved adjustable offset tool holder.

Fig. 2 is a fragmentary vertical section 30 taken approximately on the line II—II of Fig. 1.

Fig. 3 is a vertical section taken on the line III—III of Fig. 1.

Fig. 4 is a horizontal section taken approximately on the line IV—IV of Fig. 1.

Referring to the drawings, this improved adjustable offset tool holder comprises a body portion 1 having a rearwardly extending portion 2, and formed in said rear portion 2 is a pair of parallelly arranged sockets 3 and 4.

Formed in the front face of the body portion 1 is a slot or recess 5 extending the height or length of said body portion, said 45 slot being closed by the front plate 6, and formed in said front plate is a longitudinal opening 7 which communicates with and is in alinement with the slot 5.

Secured to the end 8 of the body portion 1 50 is a removable cover plate 9, having an opening 10 formed therein, and mounted in said opening is an interiorly threaded bushing 11 having an annular shoulder 12 formed at one end, said shoulder being engaged against 55 the inner face of the plate 9, and is clamped

between said plate and the end 8 of the body portion 1.

Adapted to bear on the outer face of said plate 9 and secured to the bushing 11 by the set screw 13 is a collar 14, said collar 14 and bushing 11 comprising a micrometer set 15. Movable mounted in the slot 5 of the body portion 1 is a tool post 16 having a guiding portion 17 which is rectangular in cross section, said post also having a threaded portion 18 which extends through the bushing 11, the threads thereof being in engagement with the threads of said bushing.

Longitudinally formed in the threaded portion 18 of the post 16 is a centrally arranged opening 19, and mounted in said opening is a clamping screw 20 having a squared end 21, and a threaded end 22, said threaded end 22 engaging the interior threads 23 which are formed adjacent the inner end of the opening 19 of the post 16.

Formed in the tool post 16 intermediate of its ends is a transversely arranged clamping block opening 24 which contains a clamping block 25, said clamping block having a groove 26 formed in one of its faces, said grooved face adapted to be engaged against the shank portion 27 of a cutting tool 28 when the shank portion of said tool is mounted in the recess 29 which forms part 85 of the opening 24 formed in the tool post 16, as shown more clearly in Fig. 2.

Arranged between the sockets 3 and 4 of the body portion 1 and at right angles thereto is an opening 30 through which is passed a draw bolt 31, said draw bolt having a clamping surface 32, which is adapted to engage respective shanks that are secured in the respective sockets 3 and 4.

Formed on said draw bolt is a threaded portion 33 on which is mounted a nut 34.

In the operation of this improved adjustable off-set holder, the same can be used in connection with the shank 35 of a boring bar, or a revolving spindle of drill presses, 100 milling machines or the like, or can be used in connection with a lathe, in which it is required that the tool holder be stationarily held.

When it is desired to use this improved tool holder in connection with a revolving spindle, the introducing portion 36 of the revolving shank 35 is engaged in the socket 3 of the body portion of the tool holder, and in which position it is approximately 110

centrally arranged relative to the body portion 1 thereof thereby balancing the tool holder. The draw bolt 31 is then drawn by manipulation of the nut 34 until the clamping surface 32 thereof securely engages the portion 36 of the shank 35 thereby fixedly securing the body portion 1 of the tool holder to said shank.

The tool 28 is then mounted in the recess 29 of the tool post 16, said tool being securely held in said recess by the clamping block 25 when the clamping screw 20 is tightened. Proper adjustment to the tool 28 is given by manipulation of the micrometer set 15 which will cause the tool post 16 to slide in the recess 5 of the body portion 1 of the tool holder, thereby moving the cutting edge 37 of the tool 28 toward or away from center of the work as desired.

When the shank 35 is revolved, this improved tool holder will be carried therewith, and incidentally the tool 28 will engagingly revolve around the work. When this improved tool holder is to be used in connection with the lathe to which the same is to be stationarily held, after the revolving shank 35 has been disconnected therefrom, the lathe tool post shank 38 is engaged in the socket 4 which is lowermost in the body portion, such position of engagement of the shank 38 with the body portion 1 and the tool post of the lathe holding the lower end of the body portion above the lathe bed so that the tool 28 or any other desired tool carried by the tool holder will be in close proximity to the working center of the lathe chuck which is arranged above the lathe bed.

In securing the tool holder to the lathe tool post shank 38 the draw bolt 31 is drawn until the clamping surface 32 thereof securely engages the socket engaging portion of said shank.

From the aforesaid description it is to be

noted that this improved tool holder is co-operative relative to being used in a stationarily held position or to be revolved.

What I claim is:

1. A tool holder comprising a body portion, a tool adjustably carried by said body portion, means provided on said body portion whereby a revoluble element can be secured to said body portion, and other means whereby said body portion can be secured to a stationarily held element and clamping means carried by said body portion coöperable with either one of said elements. 50

2. A tool holder comprising a body portion, an adjustable tool post carried by said body portion, a tool carried by said post, means provided on said body portion whereby a revoluble element can be centrally secured to said body portion, and other means 55 whereby said body portion can be secured to a stationarily held element in an elevated position. 60

3. A tool holder comprising a body portion, an adjustable tool post carried by said body portion, a tool clamping member carried by said post and extending therefrom, a tool carried by said post and secured thereto by said clamping member, said body portion having a pair of securing sockets 75 formed therein for securing said body portion to either a revolving or a stationary element and securing means for said elements coöperably located in said sockets. 70

4. A tool holder comprising a body portion, an adjustable tool post carried by said body portion, said body portion having a pair of spaced apart parallelly arranged sockets formed therein, each of said sockets being for the reception of a different holding element, and a drawing and clamping member mounted in said body portion between said sockets for coöperation with said holding elements. 80 85

CECIL L. HOLLINGSWORTH.
